UNITED STATES PATENT OFFICE.

AUGUST C. MILLER, OF TAUNTON, MASSACHUSETTS, ASSIGNOR TO REED
AND BARTON CORPORATION, OF TAUNTON, MASSACHUSETTS.

DESIGN FOR A MOUNTING FOR SILVERWARE.

SPECIFICATION forming part of Design No. 36,603, dated October 27, 1903.

Application filed September 25, 1903. Serial No. 174,665. Term of patent 14 years.

To all whom it may concern:

Be it known that I, AUGUST C. MILLER, of
Taunton, in the county of Bristol and State
of Massachusetts, have invented a new, origi-
5 nal, and ornamental Design for a Mounting
for Silverware; and I do hereby declare the
accompanying drawings to be a full, clear,
and exact illustration of the same, and which
said drawings constitute part of this specifi-
cation, and represent, in—

Figure 1, a side elevation or plan view of a
mounting embodying my design, showing one
end portion thereof without ornamentation or
finished appearance; Fig. 2, a side or plan view

of the same, showing both end portions with 15
ornamental finish.

I claim—

The ornamental design for a mounting for
silverware, as shown.

In testimony whereof I have signed my 20
name to this specification, in the presence of
two subscribing witnesses, on this 10th day
of September, A. D. 1903.

AUGUST C. MILLER.
